A. R. Bartram

UNITED STATES PATENT OFFICE.

A. R. BARTRAM, OF REDDING, CONNECTICUT.

RUNNING-GEAR OF VEHICLES.

Specification of Letters Patent No. 26,406, dated December 13, 1859.

To all whom it may concern:

Be it known that I, A. R. BARTRAM, of Redding, in the county of Fairfield and State of Connecticut, have invented a new 5 and useful Improvement in Wheel-Vehicles; and I do hereby declare that the following is a full, clear, and exact description of the same, reference being had to the annexed drawings, making a part of this specification, in which—

Figure 1, is a front view of the portion of a wheel vehicle which refers to my improvement. Fig 2, is a plan or top view of the same. Fig. 3, is a transverse section of the 15 same, taken in the line x, x , Fig. 1.

Similar letters of reference indicate corresponding parts in the several figures.

This invention relates to a novel mode of attaching the front bolster of the vehicle to 20 the front axle substantially as hereinafter described, whereby a positive or rigid attachment of the thills or draft pole to the front axle is obtained, and all unnecessary play and rattle hitherto consequent on said 25 attachment avoided and a more durable and desirable vehicle obtained.

To enable those skilled in the art to fully understand and construct my invention I will proceed to describe it.

30 A, represents the front axle of a vehicle and B, the front bolster. The axle may be constructed in the usual or any suitable way and its wheels attached to it in any of the known ways, the present invention depending on no peculiarity of construction 35 in either of the above named parts.

The bolster B, may be wholly of cylindrical form, at all events, two portions of it a, at equal distances from its ends must be 40 of cylindrical form in order to receive sleeves C, C, which may turn freely thereon. These sleeves are of metal and they are at the upper ends of uprights b, b, which are at the ends of a bar c. The sleeves C, C, are 45 retained in proper place on the bolster, that is to say, prevented from moving longitudinally thereon by means of metal collars d, d, which are permanently attached to the bolster at the outer sides of the sleeves.

50 The sleeves C, C, uprights b, b, and bar c, may be of malleable cast iron and the center of the bar c, has a circular plate d', recessed at its under side to receive a circular plate e,

attached to the axle A, a pin or bolt f, passing through the centers of the plates d', 55 e, see Fig. 1, the above parts forming what is generally termed a "circle plate."

The plate e, is attached to or forms a part of a bar g, which is permanently secured to the upper surface of the axle A, 60 at its central part by clips h, the two bars c, g, being one over the other when the bolster and axle are in the same plane.

D, D, represent thills or shafts which may be of usual construction. These thills or 65 shafts are attached at their back ends directly and rigidly to the axle so that as the thills or shafts are raised and lowered the axle A, will turn or swing on the bolster B, in consequence of the attachment formed by 70 the sleeves C, C.

From the above description it will be seen that a good circle plate may be used and interposed between the axle and bolster and a perfect bearing obtained equally so, as in 75 vehicles of ordinary construction and, at the same time in consequence of the attachment of the axle A, to the bolster B, the axle as before stated, is allowed to swing and admit of a positive or rigid attachment 80 of the thills or draft pole to it.

I am aware that wheel vehicles have been previously constructed with the thills attached permanently and rigidly to the front axle, but, so far as I am aware no means 85 have been devised to admit of a swinging of said axle with a proper connection to its bolster. I believe that a loose king bolt has only been used, the turning of the axle 90 when fitted in the axle. It will readily be seen that this arrangement must be attended with great wear and a rattle which is extremely unpleasant and a great objection to a pleasure vehicle.

95 I would remark that the ordinary elliptic or the longitudinal side springs may be used. If the elliptic springs are used, the ordinary perch coupling would be required.

I do not claim the attaching of the thills 100 or draft pole of a wheel vehicle permanently and rigidly to the front axle for this has been previously done, but,

I do claim as new and desire to secure by Letters Patent,

105 Attaching the front axle A, to the bol-

ster B, by means of the sleeves b, b, fitted loosely on the bolster and connected with the bar c, which is attached to a circle plate or any suitable swivel connection between the said bar and axle, when said parts, substantially thus arranged, are used in connection with thills or a draft pole attached

rigidly to the axle A, for the purpose set forth.

A. R. BARTRAM.
